EXTENSION LEAF TABLE

Joseph Cooper, New York, N. Y.

Application July 9, 1936, Serial No. 89,903

3 Claims. (Cl. 311—56)

A characteristic of the present invention is the provision of one or more extension leaves associated with a primary centrally disposed table leaf movable vertically and actuated and controlled in such movements by cam members operatively connected to the extension leaves. If more than one extension leaf is employed, there will be a plurality of cam members, one or more for each leaf.

10 A specific object of the invention is to provide a table of the said type having a simple and inexpensive construction, and which will be positive in its action, the cam member or members being simple in form and capable of stamping 15 by a single stamping operation from sheet metal.

The invention will be described with reference to the accompanying drawings, in which:—

Figure 1 is a plan view, partly broken away, 20 showing certain elements in dotted lines, embodying the invention.

Figure 2 is an enlarged longitudinal section on the line 2—2, Figure 1.

Figure 3 is a perspective view of one of the 25 supporting and control bars for an extension leaf.

Figure 4 is an enlarged perspective view of the central section of one of the supporting and control bars carrying one of the operating cams 30 for the central leaf of the table.

Figure 5 is a transverse section on the line 5—5, Figure 4.

Figure 6 is a transverse section of the table with two extension leaves in closed position, the 35 section being taken generally in the same plane as line 8—8, Figure 1, looking in the direction of the arrows.

Figure 7 is a transverse section of the table, similar to Figure 6, showing one of the extension 40 leaves moved outwardly somewhat short of its final outward position.

Figure 8 is a view similar to Figure 7, showing both leaves after they have been moved outwardly to extended position and then inwardly 45 to final extended position.

Figure 9 is a view similar to Figure 8 showing one of the leaves moved back to closed position and the right-hand leaf moved outwardly to extreme position preparatory to its return under the central leaf, and to closed position.

Figure 10 is a view similar to Figure 9, showing the right-hand extension leaf moved from the position of Figure 9 part way under the central leaf, the action of the cam being illustrated.

55 Figure 11 is a perspective view of the fixed

guiding support carried by the major bar for the central leaf and having a guiding and supporting action upon the extension leaf bars.

Figure 12 is a view in bottom perspective of a corner fragment of one of the extension leaves 5 showing the position of one of its supporting and control bars thereon.

The invention is adapted for a table constructed with a central leaf and one or more extension leaves, each having a rectangular frame 10 as of wood, covered with metal. However, the leaves may be primarily of wood omitting the metal covering, if desired.

The table may comprise a usual major frame 15 comprising longitudinal frame members such as the frame member 1 illustrated in Figure 2, which may be directly attached each to two of the legs 2, each set comprising a longitudinal frame member and two legs 2, being connected by transverse frame members 3.

Supported on transverse frame members 3 centrally thereof, is a primary supporting bar 4 for the primary leaf of the table, this leaf comprising the longitudinal frame pieces 5, transverse frame pieces 6 and longitudinal centrally disposed frame piece 5x. The frame pieces 5, 5x and 6 are covered by metal sheathing 7.

The primary leaf is vertically movable. To guide the leaf in its movements central frame piece 5x carries the depending guide studs 8 which 30 are vertically movable in bushing sleeves 9 carried by primary supporting bar 4, as shown more particularly in Figure 2.

Each extension leaf may comprise the longitudinal frame pieces 10 and transverse frame 35 pieces 11 covered by a metal sheathing 12. Each extension leaf has connected at its underface and to an appropriate longitudinal frame member 10, two or more supporting and control bars 13.

Each bar 13 is longitudinally grooved at its 40 opposite side faces, the grooves being indicated at 13x, Figure 3, and into each groove is projected one arm 14x carried by a fixed guiding support 14, shown in Figure 11. There is in the present embodiment one fixed guiding support 45 14 for each extension leaf bar 13, each support 14 being secured to the underface of primary supporting bar 4 as shown more particularly in Figures 1 and 6 to 10 inclusive. Grooves 13x are of greater width than the thickness of the 50 arms 14x of fixed guiding support 14 to enable a necessary transverse movement of bars 13 in the operation of the extension leaves as will later be explained.

In my construction the center leaf 1 is positively 55

raised in the outward movement of either extension leaf by reason of the fact that the control bars 13 are mounted for movement angularly of the center leaf 7 and therefore in the outward movement of an extension leaf its upper surface will bear upon the underlying frame of the center leaf and will cause it to raise in the manner shown in Figure 7.

When the extension leaf has been moved to a position clearing the center leaf, the latter will drop by gravity, and thereupon the extension leaf may be moved inwardly to Figure 8.

The function of the operating cams 15 is to hold the center leaf upwardly during the beginning of a closing movement of the appropriate leaf. To this end, in closing the table, the appropriate extension leaf is moved outwardly from its position shown in Figure 8 to the position of Figure 9. This will cause the appropriate cams 15 to be carried over upon the appropriate frame members 1 and in bearing relation with the overlying frame member 5 of the center leaf, the parts assuming the position shown in Figure 9 wherein the depending fingers of the appropriate cams 15 engage the innerface of the adjacent frame member 1 preventing further outward movement of the extension leaf. The latter may then be moved inwardly, pins 16 riding idly in the center apertures of the appropriate cams 15 until the extension leaf is placed under the center leaf as shown in Figure 10. Further inward movement of the extension leaf will carry the cams out of engagement with frame member 1 and they will drop idly to the position shown in Figure 6 when the extension leaf has been moved to fully closed position, the flange 15a engaging, in each case, the top of the control bar in which the cam is mounted.

Having described my invention, what I claim and desire to secure by Letters Patent is as follows:

1. An extension leaf table comprising a frame, a primary leaf mounted for vertical movement on the frame, an extension leaf normally under-

lying the primary leaf, and a cam member formed with a slot, a connection between the cam member and the extension leaf including a contact member entering the slot of the cam member, the extension leaf having a limited movement outwardly without transferring movement to the cam member, continued outward movement of said leaf causing the contact member to engage the cam and effecting movement of the latter against the underface of the center leaf, raising the latter; reverse movement of the leaf causing idle movement of the contact member in the cam slot.

2. An extension leaf table comprising a frame, a primary leaf mounted for vertical movement on the frame, an extension leaf mounted for movement from under the primary leaf to outward position laterally thereof, a plurality of control bars slidably movable upon an underlying member of the frame and carrying the extension leaf guiding means for confining the movement of the extension leaf to an inclined plane intersecting the normally horizontal plane of the primary leaf top, a guide slot formed in each control bar, a cam mounted for both vertical and endwise movements in each guide slot and having a longitudinally extending passageway, and a stud carried by the said bar and entering the passageway of the cam for positively moving the same endwise, the said passageway being adapted to permit substantial vertical movement of the cam relatively to said stud.

3. An extension leaf table constructed in accordance with claim 1, in which the cam is formed with an uppermost laterally extended flange adapted to engage the upper surface of the control bar, the cam also being formed with a wedge-like slot, the faces of the cam at the opposite ends of the slot providing the contact faces for the contact member carried by the control bar, and the cam being provided at its rear portion with a depending finger.

JOSEPH COOPER.
